UNITED STATES PATENT OFFICE

WALTER D. JARVIS, OF PITTSBURGH, PENNSYLVANIA, ASSIGNOR, BY MESNE ASSIGNMENTS, TO MARY HAINES MARKS, OF SEWICKLEY, PENNSYLVANIA

PAPER LATH

Application filed May 31, 1930. Serial No. 458,068.

My invention pertains to paper lath and relates especially to paper lath of the character in which a backing of corrugated paper, or paper-like material, having metallic stiffening devices secured thereto is employed.

In building construction, it has become common to employ what is known as paper lath, that is to say lath constituted by a backing of paper, or paper-like material, to which is applied plaster, concrete or kindred cementitious substances such as are used in building construction, which substances are intended to be included when the term "plaster" is used herein. Paper formed with corrugations has been found to be desirable for the backing, since the plaster, filling the corrugations, is keyed to the backing, and also the corrugations produce projections, at the rear of the backing, which space the lath in a desirable manner from the studding or other support which is to carry the plaster. It is found in practice, however, that such corrugated paper backings tend to sag, and the corrugations thereof to straighten out, when the wet plaster is applied thereto. Various undesirable conditions result from this. For instance, when the lath is employed horizontally, the backing, and the whole body of plaster, is liable to sag downwardly. On the other hand, when the lath is employed vertically, the backing is liable to sag inwardly under the pressure of the trowel or other implement by means of which the plaster is applied, and subsequently, after the plaster has been applied, to spring outwardly, the result being that the surface of the plaster is waved instead of flat. Various means have been proposed from time to time to prevent collapse of the corrugations in such paper backings, and to stiffen the whole backing against sagging. However, such constructions have been expensive and not entirely satisfactory in the results obtained.

It is the principal object of my invention to provide paper lath including a corrugated paper backing which will be proof against collapse of the corrugations and sagging of the backing, and which will be of an exceptionally economical construction. It is a further object of my invention to provide

such paper lath having means for stiffening the same against sagging, in which the stiffening means constitute a keying means for the plaster and also operate as a reinforcement for the latter. Still another object of my invention is to provide paper lath having stiffening means, of such a character that adjoining sections can be readily lapped one over the other, thereby reducing the number of nails or other means necessary for securing the lath to the studs or the like and at the same time avoiding any diminution of supporting power along the lines where the lath sections adjoin each other. And other and further objects of the invention will appear from the following specification, taken in connection with the claims annexed thereto.

By way of example, I have described in the following specification, and shown in the accompanying drawing, one form of paper lath embodying my invention. It is to be understood, however, that the invention may be embodied in other forms, and changes made in the form described and shown, without exceeding the scope thereof as defined in the appended claims.

In the drawing, Fig. 1 is a front view showing sections of paper lath embodying my invention as applied to studding; Fig. 2 is an enlarged front view of a corner of a lath section; Fig. 2-a is an enlarged detail section through one of the bridge members, the section being taken on the line IIa-IIa of Fig. 2; Fig. 3 a cross-section taken on the line III-III of Fig. 2; and Fig. 4 is a fragmentary view showing a modification.

Referring now to the drawing, the section of paper lath shown therein comprises a backing sheet of paper (which term is intended herein to include paper-like materials in general) in which are formed a series of spaced V-shaped corrugations 2. These corrugations run lengthwise of the backing sheet, which is of an elongate rectangular form suitable to span a plurality of the studs 3 or other supports to which the plaster is to be applied, the V-shaped corrugations then running transversely of such studs. In certain of the corrugations 2 (in the instance

shown in the top, bottom and middle corrugations) are disposed V-shaped metallic stiffening strips 4 which, in the particular embodiment shown, are of a shape corresponding with that of the corrugations 2 and arranged so that their edges are flush with the surface of the backing sheet 1, though such shape and arrangement may be varied. Spaced along the length of the backing sheet, 10 at right angles to the corrugations 2, are sheet metal bridge members 5, of U shape in cross section, these members being secured in place by staples 6, one at each corrugation. The staples 6 bridge the corrugations 2 diagonally, their ends being passed through the backing sheet and crimped down at the back of the same, as indicated at 6a, close to the edges of the corrugations. The operation of applying the staples causes indentations 20 5a (Fig. 3) to be formed in the bridge members 5 at the points where the staples cross such bridge members, whereby the bridge members are securely locked against longitudinal movement. At the points where the bridge members 5 cross the stiffening strips 4, the staples hold the bridge members firmly down on the stiffening strips, thereby producing a structure which is firm and rigid as a whole.

30 The above-described construction of lath is such that the sections are relatively rigid, giving a very firm support to the plaster and being easily handled. An important feature is that while stiffening members are employed, the end parts of the sections are nevertheless capable of nesting one on the other,—by reason of the V shape of the members 4, the fact that the last bridge members 5 are located at a substantial distance from the ends of the sections, and the fact that the ends of the sections are unobstructed by reinforcing nettings or the like. When the sections are made somewhat longer than the distance spanning the centers of a plurality of the studs 3, this allows the end of one section to be overlapped on the end of the adjoining section and the two sections to be secured in place by a single set of securing means, as by driving nails 7 so as to pierce the overlapped stiffening members 4 and enter the studs 3. This reduces by one-half the nails and nailing time necessary in securing the ends of the lath sections to the studs, and, in addition, provides a firm and secure joint between the sections. Other nails, indicated at 7', may be employed for securing the intermediate portions of the sections to the intermediate studs.

33 As an alternative to making the sections longer than the distance spanning a plurality of the studs, the stiffening members 4 may be made to extend somewhat beyond the ends of the paper backing, as indicated at 4a in Fig. 4. With this construction the ends of the backing portions 1 of the sections would

be butted against each other on a stud. The ends of the stiffening members 4a of the adjoining sections would, however, overlap and be secured by nails passing through the overlapping stiffening members, as before.

70 In the paper lath of my invention provision is effectively made against sagging of the paper backing sheet and/or opening out of the corrugations thereof. The backing being securely bound to the stiffening strips 4 and bridge members 5 cannot, of course, sag away from them, either by reason of the weight of the plaster or of the pressure of the trowel. Opening out of the corrugations, which has heretofore been a source of trouble in paper lath of this general type, is the result, of course, of a tendency of the backing sheet to sag and is avoided when such tendency is obviated, as is the case with my construction. Moreover, as the bridge members 5 are secured to the backing at the corrugations, and as the staples cross the corrugations and are secured on both sides of the latter, any distortion of the corrugations is impossible. The paper lath of my invention has further advantages, an important one of which is that the plaster enters corrugations 2 and extends around and behind the bridge members 5, whereby the plaster becomes keyed to the backing. Also, the plaster enters the grooves of the U-shaped bridge members 5, which latter become partly or wholly embedded in the plaster, whereby the plaster is further and very securely keyed to the backing and, in addition, is reinforced to an important extent. An additional advantage is that the paper lath is exceptionally economical of manufacture, being readily produced by automatic machinery and the elements thereof being of relatively small cost.

I claim:

1. Paper lath comprising a paper backing sheet formed with longitudinal corrugations, individual bridge members extending transversely of said corrugations and formed with indentations at points where they cross the latter, and staples securing said bridge members to said sheet, said staples resting in said indentations.

2. Paper lath comprising a paper backing sheet formed with longitudinal corrugations and individual bridge members extending transversely of said corrugations and secured to said backing sheet, said members being of hollow structure to permit entry of plaster therein, whereby portions of said members become embedded in plaster and said members constitute reinforcing and keying means for the plaster.

3. Paper lath comprising a paper backing sheet formed with longitudinal corrugations and individual bridge members extending transversely of said corrugations and secured to said backing sheet, said members being of

U-shape and disposed with their sides resting on said sheet, whereby portions of said members become embedded in plaster and said members constitute reinforcing means for the plaster.

4. Paper lath comprising a paper backing sheet formed with longitudinal corrugations, individual bridge members extending transversely of said corrugations and staples securing said bridge members to said sheet each staple spanning a corrugation and entering the sheet beyond each side of the latter so as to preserve the shape of the corrugation.

5. Paper lath comprising a paper backing sheet formed with longitudinal corrugations, a stiffening member disposed in one of said corrugations, individual bridge members extending transversely of said corrugations and staples securing said bridge members to said sheet each staple spanning a corrugation and entering the sheet beyond each side of the latter so as to preserve the shape of the corrugation.

6. Paper lath comprising a paper backing sheet formed with a series of longitudinal corrugations, stiffening members disposed in certain but not all of said corrugations, individual bridge members extending transversely of said corrugations, and staples securing said bridge members to said sheet each staple spanning a corrugation and entering the sheet beyond each side of the latter so as to preserve the shape of the corrugation.

In testimony whereof, I sign my name.

35 WALTER D. JARVIS.
